WILLIAM G. HALL, OF MANILA, PHILIPPINE ISLANDS, ASSIGNOR OF ONE-HALF TO
ROY C. PITCAIRN, OF HONOLULU, TERRITORY OF HAWAII

CRYSTALLIZER

Application filed July 31, 1929. Serial No. 382,309.

The invention relates to crystallizers for sugar juices and has for its object to provide a novel form of apparatus, including a tank with a helical stirrer mounted on a horizontal axis therein so as to be completely submerged in the liquor, a second helical stirrer mounted above the first so as to be only partially submerged in the liquor and to continuously lift portions of the liquor from the body of the latter and drop the same through the air back into the tank to effect a uniform cooling of the liquor and thereby expedite the formation of the sugar crystals.

The invention is illustrated in the accompanying drawings, in which:—

Fig. 1 is a longitudinal sectional elevation of the crystallizer.

Fig. 2 is a fragmentary perspective view of a modified form of the upper stirrer and elevator.

In the process of making sugar from cane or beet juice, it is necessary to concentrate the liquor to such an extent that crystallization takes place. The crystals of sugar formed are separated from the molasses or mother liquor in centrifugals. The molasses from the first sugar, which is made from syrup, contains a comparatively high percentage of sugar and this molasses is boiled again and makes a lower grade of sugar. In handling the massecuite made from molasses, it has been found advantageous to retain the massecuite, after it has been boiled in the vacuum pans, in tanks or crystallizers. These crystallizers are usually provided with a stirring device, which keeps up a slow circulation of the massecuite, thereby promoting the growth and development of the small grains or crystals of sugar which were formed in the vacuum pan. This operation is known in the art as crystallization in motion and the massecuite is usually retained in the crystallizers for approximately six days before it is put through centrifugals, where the crystals are separated from the molasses. It has been found that cooling the massecuite uniformly and rapidly promotes crystallization, so that, when proper cooling is effected, the time necessary to retain the massecuite in the crystallizers is greatly reduced and the resultant

massecuite is more easily worked in the centrifugals, and also results in a decided saving in crystallizer capacity, or, in other words, increases the efficiency of this part of the sugar making process to a decided degree.

It has been found, in practice, that by operating a crystallizer only partly filled with massecuite and permitting the stirring apparatus to operate approximately half in and half out of the liquor, crystallization takes place much more rapidly than when the crystallizer is filled to capacity and the stirring apparatus is completely submerged in the liquor. While this results in expediting crystallization, the advantage is somewhat offset by the reduction in the output of a given crystallizer which is operated at only about half capacity. The present invention is designed to provide a crystallizer of the stirrer type that will maintain the proper circulation of the liquor in the tank and will also include the advantageous operation of the partially submerged stirrer, which picks up the liquor from the tank, carries the same through the air above or in the upper part of the tank and drops it back in the form of thin sheets or streams into the tank, thereby effecting the rapid and uniform cooling necessary to expedite the formation of the sugar crystals.

A relatively simple form of apparatus involving the invention is shown in Fig. 1 of the drawings, in which 1 represents the tank of the crystallizer, which is provided with an open top. Journaled in bearings 2, 2 in the lower part of the tank is a horizontal shaft 4 carrying a helical stirrer 8, preferably in the form of a sheet metal strip attached to the shaft at intervals by means of radial arms 6 and clamping collars 7.

Mounted in similar journal bearings 3 located near the top of the tank is a second shaft 10 which carries a second stirrer and liquor elevator, which, as shown, is made of a strip of T-iron or two sections of L-iron connected together to provide relatively extensive surface areas, which, in passing through the liquor, will pick up and carry portions of the liquor into the air above and drop the same in thin streams or sheets back into the tank. The two helical stirrers

are so disposed that the successive curved portions thereof intermesh as the stirrers rotate and uniform rotary motion is imparted to each by suitable gearing, exemplified in the present case by intermeshing gears 14 and 15 of the same size, the gear 14 being driven by a worm 16.

In operating the crystallizer, the tank is filled to capacity, so that the lower helical stirrer operates in completely submerged relation, while the upper stirrer is only partly submerged, so that, as the helical blade rotates, it operates to pick up portions of the liquor, pass the same through the air and drop it in the form of thin sheets or streams 15 into the tank, with the result that the liquor is rapidly and uniformly cooled and the crystallization of the sugar therein commensurately expedited.

20 Instead of forming the helical portion of the upper stirrer of a T cross section, as shown in Fig. 1, the helical member may be formed of a series of spaced parallel blades or strips 13 with their edges normal to the 25 axis of rotation, which will largely increase the lifting and carrying capacity of the stirrer blade and insure the liquor being dropped from the stirrer, as the latter passes through the air in the form of thin sheets 30 or streams, which will still further accelerate the uniform cooling of the liquor.

What I claim is:

1. A crystallizer comprising a tank to receive the liquor to be operated upon, a stirrer 35 mounted in the tank and operating under conditions of complete submersion in the liquor, and a second stirrer similarly mounted only partially submerged and operating to pick up portions of the liquor and drop 40 the same through the air back into the tank.

2. A crystallizer comprising a tank to receive the liquor to be operated upon, a stirrer mounted in the tank and operating under conditions of complete submersion in the 45 liquor, and a second stirrer similarly mounted only partially submerged and operating to pick up portions of the liquor and drop the same in thin sheets through the air back 50 into the tank.

3. A crystallizer comprising a tank to receive the liquor to be operated upon, a helical stirrer mounted on a horizontal axis and submerged in the liquor, and a second helical stirrer similarly mounted and operating partially in the liquor and partially in the air; whereby portions of the liquor are picked up 55 by the second stirrer and dropped through the air back into the tank.

4. A crystallizer comprising a tank to receive the liquor to be operated upon and two intermeshing helical stirrers mounted on horizontal axes in said tank, one stirrer operating in complete submersion and the other in partial submersion in the liquor in the 65 tank.

5. A crystallizer comprising a tank to receive the liquor to be operated upon, horizontal shafts journaled in the upper and lower portions of said tank, a helical stirrer blade carried by the lower shaft in complete submersion, and a helical stirrer and liquor lifter carried by the upper shaft and operating partly in and partly out of the liquor.

6. A crystallizer comprising a tank to receive the liquor to be operated upon, horizontal shafts journaled in the upper and lower portions of said tank, a helical stirrer blade carried by the lower shaft in complete submersion, and a helical stirrer and liquor lifter including a series of spaced parallel 80 blades with their edges normal to the axis of rotation carried by the upper shaft and operating partly in and partly out of the liquor.

In testimony whereof I affix my signature. 85
